UNITED STATES PATENT OFFICE

156,285

DESIGN FOR A CRIBBAGE BOARD OR SIMILAR ARTICLE

Richard H. Sleeman, Toronto, Ontario, Canada

Application January 29, 1948, Serial No. 144,132

Term of patent 3½ years

(Cl. D34—5)

To all whom it may concern:

Be it known that I, Richard H. Sleeman, a citizen of the Dominion of Canada, resident of the city of Toronto, in the Province of Ontario, Dominion of Canada, have invented a new, original, and ornamental Design for a Cribbage Board or Similar Article, of which the following is a specification, reference being had to the accompanying drawing, forming part thereof.

Fig. 1 is a plan view of a cribbage board or similar article showing my new design. The surface of the board is shaded to show color contrast.

Fig. 2 is an edge view of the board.

The markings on the board are surface representations only.

I claim:

The ornamental design for a cribbage board or similar article, as shown and described.

RICHARD H. SLEEMAN.
